HONE

Harold L. Blood, Worcester, Mass., assignor to
 The Heald Machine Company, Worcester,
 Mass., a corporation of Massachusetts

Application September 14, 1936, Serial No. 100,580

16 Claims. (Cl. 51—184.2)

The present invention relates to a hone especially adapted for the finishing of internal surfaces, as for example, the outer raceways of roller or ball bearings, and is especially directed to an arrangement by which the individual honing stones may all be held in contact with the work at all times.

In prior devices of this character, in which the hone is made up of a plurality of similar honing members all held in a position for simultaneous engagement with the workpiece, the honing material has generally been held rigidly against the surface being honed, although in certain instances, as for example in the device of the Stimson Patent No. 1,418,847, dated June 6, 1922, the honing material is mounted resiliently on the spindle to accommodate the material to small variations in workpiece diameter. The resiliency in the Stimson structure is provided by rubber pads which are not required to compensate for wear as the abrasive material is in the form of sheet material having an abrasive coating, so that there can be no substantial wear without complete destruction of the abrasive. A compensation for wear on the individual honing members has thus never been provided, and accordingly the principal object of the present invention is to provide a resilient mounting for each individual honing member so that where a plurality of stones are used each member will be held against the workpiece with substantially the same pressure regardless of wear on the member and regardless of variations in diameter of the workpiece.

Where the surface being honed is tapered the honing members must be arranged to conform to this taper. One form of a hone suitable for tapered workpieces is disclosed in applicant's pending application Serial No. 69,861, filed March 20, 1936, in which a resilient arrangement is provided for holding the several honing stones all against the workpiece being honed. This resilient arrangement permits an axial reciprocation of the workpiece relative to the honing members, since the several members can all move radially of the support on which they are mounted. In the event of rapid wear of one of the honing members in a hone of this character the single resilient mechanism provided will not hold the worn member against the workpiece with the same force that the other less worn members are held. It is a further object of the present invention to provide for holding all of the honing members against the workpiece with substantially equal pressures independently of varia-

tions in the rate of reduction in size of the individual members by wear, and independently of the resilient mechanism provided for expanding the hone.

Other and further objects and advantages of the invention will hereinafter more fully appear from the following detailed description taken in connection with the accompanying drawing in which

Fig. 1 is a side elevation, partly in section, of a hone embodying the invention.

Fig. 2 is an end elevation of the hone of Fig. 1.

Fig. 3 is an elevation of one of the elements of the hone.

Fig. 4 is a side elevation of the hone head.

Like reference characters refer to like parts in the different figures.

With reference to Fig. 1, the hone comprises a head or arbor 1, see also Fig. 4, having an axial bore 2 in which a spindle 3 is slidable. The head 1 has a key 4 engaging with a keyway 5 in the spindle to hold the latter against rotation. The spindle 3 has an arcuate shoulder 6 positioned within the head, and the end of said spindle projects beyond the head and has a cap 7 secured thereto. The opposite end of the spindle has an axially positioned bolt 8, held against turning by a locking nut 9. A cylindrical hub 10 on the head provides for attachment of said head, with the honing members mounted thereon, to the end of a rotatable spindle 11 of any suitable character. The spindle 3 is shown as made up of two separate members, but these members are functionally integral and are so described.

The head 1 has a plurality of radially extending slots 12, Figs. 2 and 4, in each of which is positioned a lever 13 substantially of bell-crank form. At the corner of each lever is an arcuate protuberance 14 engageable with the arcuate shoulder 6 on the hone spindle 3, thus permitting oscillation of the lever about this point.

Surrounding the head 1 adjacent the base of the slots 12 is an annular member 15 secured to the head, as by bolts 16, said annular member having a flange 17 engaging in a recess 18 in the head to hold the member in position. Between the member 15 and the head is clamped a resilient disk 19 in the form of an annular diaphragm, having resilient fingers 20 extending inwardly of the annular member, with one finger located in each of the notches 12.

Each lever 13 has an arcuate lug 21 at one end thereof for engagement with the inner or right hand (Fig. 1) side of the corresponding finger 20 on the disk to permit rocking movement of said

lever about the lug. The opposite end of the lever 13 is tapered with the inner surface thereof extending substantially parallel to and spaced from the projecting end of the spindle 3. On the outer surface of the lever at this end is an arcuate lug 22 which engages in an arcuate recess 23 in a hone carrier 24. On the outer side of each of the carriers 24 is located a plate 25 to which is secured, as by a suitable adhesive, a honing member in the form of a stone 26, generally of abrasive material. The stone is additionally held in position by flanges 27 projecting from the plate, and the plate preferably has lugs 28 engaging in recesses 29 in the carrier. 5

10 The plates are held on the carriers by coil springs 30 and 31, each arranged in the form of an annulus. The spring 30 is positioned at the inner or right hand (Fig. 1) end of the plates and engages the flanges 27. The other coil spring 20 31 is positioned in a recess 32 in the outer end of each of the plates and the inturned portion of the plate which forms this recess engages in a correspondingly shaped recess 33 in the carrier. Not only do these coil springs hold the plates 25 against the carrier, but they also hold each carrier in engagement with the corresponding lever and hold the levers against the shoulder 6 of the hone spindle 3. For holding the levers 13 in predetermined relation to each other in the 30 head a coil spring 34 is provided, also in the form of an annulus, and this coil spring is positioned in a slot 35 in the head with the spring engaging all of the levers.

The head above described is applicable to any 35 suitable type of spindle in which is incorporated a structure for expanding and contracting the hone. In the construction shown, the spindle 11, on which the head is mounted, has an axial bore 36 in which the inner end of the spindle 3 is 40 received. Within the spindle is located an actuating rod 37 having at the end thereof a head 38 engageable with the end of the bolt 8, and the rod, with the head thereon, is resiliently urged to the left by a compression coil spring 39 45 rounding the rod. The remainder of the spindle is of any suitable character, one example being fully shown and described in applicant's copending application, Serial No. 92,396, filed July 24, 1936, and is not a part of the present invention. 50 It is sufficient to note that the movement of the rod to the left, Fig. 1, is preferably limited to prevent the honing stones from being expanded by the coil spring to such an extent that they cannot enter the bore of the workpiece to be honed. 55 The rod 37 may also have incorporated thereon a suitable mechanism for withdrawing said rod to the right to permit collapse of the hone when desired.

In operation the hone is expanded to such an 60 amount that it can enter the bore of the workpiece and engage therewith, a workpiece *a* being shown in operative engagement with the several honing stones. As the workpiece is given an axial reciprocation relative to the hone during the honing operation, the honing stones are urged inwardly as the workpiece moves to the right relative to the hones and outwardly as the workpiece moves to the left, this movement being permitted by the resilient action of the spring 39, and this 65 in and out movement of the stones causes a slight reciprocatory movement of the rod within the spindle. If any one of the stones becomes worn more than the rest, or if an uneven place is encountered in the work, the pressure exerted by 70 the spring 39 cannot compensate for the wear,

but the resiliency of the disk 19 and the fingers 20 cause the lever carrying the worn hone member to be urged outwardly to a greater extent than the other levers so that all of the stones continue to act upon the workpiece. 5

From the foregoing it will be apparent that each of the honing stones is resiliently held against the workpiece individually so that variations in the rate of wear of the several stones will not affect the operation of the hone. Where the honing members are normally held resiliently against the workpiece, as by a single resilient mechanism, this individual resilient structure is separate from the other mechanism and operates independently thereof. 10 15

I claim,

1. In a honing device, an arbor, a bell-crank lever carried thereby, one end of said lever being engageable with said arbor for rocking of said lever about said end, a honing member on the opposite end of said lever, means engaging with the corner of the lever for urging the lever and member into operative position, and a resilient connection for said lever at one point of support for resiliently urging said lever into operative position independently of said means. 20 25

2. In a honing device, an arbor, a plurality of bell-crank levers carried thereby, one end of each of said levers being engageable with said arbor for rocking of said levers about said ends, a honing member on the opposite end of each of said levers, means engageable with the corner of each of said levers for urging each lever and the member carried thereby into operative position, and a resilient connection between each of said levers and the arbor for resiliently urging each of said levers into operative position independently of said means. 30 35

3. In a honing device, a head, levers rockably mounted on said head, a honing member carried by each of said levers, means engageable with the levers to urge the levers and the members into operative position, and a resilient means acting on each lever independently of said means for resiliently urging each of the members carried by 40 45 the levers individually into operative position.

4. In a honing device, a head, levers rockably mounted on said head, a honing member carried by each of said levers, resilient means engageable with the levers to urge the levers and the members into operative position, and a resilient means acting on each lever independently of said means for resiliently urging each of the members carried by the levers individually into 50 55 operative position.

5. In a honing device, a head, a plurality of levers rockably mounted on said head with the connection between said levers and the head resilient, a honing member carried by each of said levers, and means engageable with all of the levers for urging said levers and the members carried thereby into operative position, said resilient connection providing for a resilient urging of each of said levers individually into operative position independently of the first means. 60 65

6. In a honing device, a head, a plurality of levers rockably mounted on said head with the connection between said levers and the head resilient, a honing member carried by each of said levers, and resilient means engageable with all of the levers for urging said levers and the members carried thereby into operative position, said resilient connection providing for a resilient urging of each of said levers individually into operative position independently of the first means. 70 75

7. In a honing device, an arbor, a plurality of levers carried thereby and mounted for rocking movement relative thereto, resilient fingers carried by the arbor and engageable by the levers for a resilient support of said levers, a honing member on each lever, and means engaging with all of the levers for urging said levers into operative position. 5
8. In a honing device, an arbor, a plurality of levers, a resilient connection between said arbor and each of said levers, a honing member on each lever, and means engageable with all of said levers for urging said levers as a group into operative position. 10
9. In a honing machine, an arbor, a plurality of levers, a resilient connection between said arbor and each of said levers, a honing member on each lever, and resilient means engageable with all of said levers for urging said levers as a group into operative position. 15
10. In a honing device, an arbor having a plurality of radial slots therein, a lever positioned in each of said slots and mounted for pivotal movement relative to the arbor, a resilient connection between the pivotal support of each lever and the arbor, a honing member rockably mounted on each lever, and a plunger axially slidably in the arbor and engageable with all of the levers for urging the latter as a group into operative position. 20
11. In a honing device, an arbor having a plurality of radial slots therein, a lever positioned in each of said slots and having a pivotal movement relative to the arbor, a resilient connection between the pivotal support of each lever and the arbor, a honing member rockably mounted on each lever, and a spring surrounding the arbor and engageable with the honing members for holding said members against the levers. 25
12. In a honing device, an arbor having a plurality of radial slots at one end thereof, a lever positioned in each of said slots, a ring having a plurality of resilient fingers engageable with one end of each of said levers and providing a pivotal support therefor, a honing member rockably mounted on each of said levers, springs 30
- holding said members in position on said levers, and a plunger within the arbor and engaging with each of said levers for urging the latter into operative position. 5
13. In a honing device, a honing head, a plurality of levers carried thereby and rockable relative thereto, a honing member on each of said levers, means engageable with all of said levers for urging the latter into operative position, and an individual resilient means for each of said members for urging each member separately into operative position, said individual means acting independently of the first means. 10
14. In a honing device, a honing head, a plurality of levers carried thereby and rockable relative thereto, a honing member on each of said levers, means engageable with all of said levers for urging the latter outwardly into operative position, and an individual resilient means for each of said members for urging each member separately into operative position, said individual means acting independently of the first means and compensating for uneven wear on the individual members. 15
15. In a honing device, a head, levers rockably mounted on said head, a honing member carried by each of said levers, means acting upon all of the levers to urge the latter and the members carried thereby simultaneously into operative position, and a resilient means acting on each lever for resiliently urging each of the members carried by the levers individually into operative position. 20
16. In a honing device, a plurality of levers, means for supporting said levers, one end of each lever being engageable with said means for rocking movement about said end, a honing member carried by each lever, means acting upon all of the levers simultaneously for urging said levers and the members carried thereby into operative position, and a resilient finger forming part of one of said means and engageable with the lever for resiliently urging each of said levers into operative position independently of said first urging means. 25
